UNITED STATES PATENT OFFICE

SALLY MILGRIM, OF WOODMERE, NEW YORK, ASSIGNOR TO ASSOCIATED MERCHANTISING CORPORATION, OF NEW YORK, N. Y., A CORPORATION OF NEW JERSEY

DESIGN FOR A DRESS

Application filed July 27, 1932. Serial No. 44,458. Term of patent 3½ years.

To all whom it may concern:

Be it known that I, SALLY MILGRIM, a citizen of the United States, and resident of Woodmere, Long Island, in the county of Greene and State of New York, have invented a new, original, and ornamental Design for a Dress, of which the following is a specification, reference being had to the accompanying drawing, forming part thereof.

I claim:

The ornamental design for a dress substantially as shown.

SALLY MILGRIM.
